AIR SUPPORTED STRUCTURE

Edward Neil Helmers, Newark, Del., assignor to E. I. du Pout de Nemours and Company, Wilmington, Del., a corporation of Delaware

Filed Oct. 31, 1958, Ser. No. 770,959

5 Claims. (Cl. 135—1)

The present invention relates to portable shelters and, more particularly, to air supported shelters having the shape of a section of a sphere, e.g., a hemisphere or a spheroidal section being more or less than a hemisphere.

Air supported shelters consist in brief, of a film, fabric, or similar material of low air permeability, anchored or otherwise fastened to the ground or other suitable surface and maintained in the erected state by air pressure. Provisions for ingress and egress and lighting of the interior are made, which provisions maintain the structure in a substantially pressure-tight condition. Structures up to about 100 feet in diameter have been constructed successfully. However, at diameters greater than about 100 feet, the inflation pressure necessary and the upward force caused by the velocity of wind striking the structure combine to provide stresses that currently-known films, fabrics, etc. cannot withstand.

It is the primary object of the present invention to provide a design for air supported structures having the shape of a spheroidal section that will enable such structures to withstand extremely high forces. A further object is to provide a design that will permit construction of air supported structures having diameters of 300 feet and higher that can withstand wind velocities of 70 miles per hour and higher.

Other objects and advantages of the invention will be readily apparent from the following detailed description when read in conjunction with the accompanying drawings, wherein:

FIGURE 1 is a view in perspective of the preferred embodiment of the inflated air supported structure of the present invention.

FIGURE 2 is a sectional view of the air tight means employed to secure the lower edge of the inflated air supported structure.

Briefly stated, the present invention contemplates an air supported structure having the shape of a spheroidal section comprising a plurality of gores of flexible material (film, fabric, and the like) having a common apex, the distance from the apex to both extremities of the base of each of said gores being less than the distance from the apex to a point halfway between the extremities of the base of each gore; the structure having its lower edge secured by substantially air-tight means. The limitation on the distances from apex to base provides a structure having a parachute-like appearance and one in which the lower edge has a scalloped appearance.

In one mode of carrying out the present invention, a substantially hemispherical sheet of film, tailored to provide the aforementioned gore sections of reduced radius, is pegged to the ground at its lower edge. Having been securely staked, the interior is inflated by moderate air pressure using a centrifugal fan. The shelter, thus formed, has a segmental shape due to the critical tailoring of the gores. Its lower edge appears scalloped when viewed from above. And the shelter, at its top, converges to form a single dome and apex. One or more doors, each in the form of an air lock, may be arranged at suitable points around the base of the structure depending upon the ultimate use of the structure. For the purpose of lighting, the film or fabric employed or panels or portions thereof may be transparent or translucent. Alternatively, artificial lighting may be used.

The supply of air required to maintain inflation is small in comparison to that required to inflate initially. Since

2

it is desirable to have a moderate amount of air leakage to provide ventilation within the structure, the amount of air required is that necessary to replace the amount lost due to leakage. The pressure required to maintain the structure erect under normal conditions is very low, being of the order of about .02-.03 lb./sq. in. However, when high winds are anticipated, then pressures up to 0.1 lb./sq. in. may be used.

Referring to FIGURE 1 of the drawing, the structure formed in accordance with the present invention is composed of a plurality of sections or gores 11 arranged substantially in the form of a hemisphere 10. The lower edge of the hemisphere appears scalloped due to the critical limitation imposed upon the gore sections; namely, that the distance from the apex of the hemisphere to the extremities of the base of each gore be less than the distance from the apex to a point on the base of the gore halfway between the extremities of the gore.

The reduced radii sections or gores may be obtained in several ways. The fabric or film may be a single sheet tailored to provide the aforementioned gores as integral sections when inflated. Alternatively, the fabric or film may be in the form of a plurality of gores stitched or adhered together to provide the structure of the invention upon inflation. Alternatively, the fabric or film may be a single sheet that is capable of elastic deformation. When such a smooth surface sheet is anchored to the ground by means of cables or load-carrying members extending from the center of the sheet to its outer extremities, the smooth surface upon inflation assumes a parachute-like shape due to restriction by the cables and simultaneous deformation due to stretching of the material between the cables. When cables are used, the structure tends to assume the shape of an oblate spheroid rather than a section of a sphere.

The preferred embodiment of the present invention, as shown in FIGURE 1, utilizes a combination of tailoring and elastic deformation due to the restricting load-carrying members (cables 12) to provide the critical appearance of the invention. The cables 12 extend from a crown 13, which may be of metal or other suitable material, to the foundation 14 of the structure.

The method of constructing the foundation is to dig a circular trench 19 of the necessary width and depth corresponding to the circle obtained by connecting the points representing the extremities 20 of the gores; driving a circular pipe 21 into the trench 19; and then tucking the base of the film under the pipe to make the structure substantially air-tight at the base. Instead of a pipe as described, wooden piles, concrete piles, concrete footers, or ground anchors may be used in a similar manner to achieve the same purpose. Upon inflation, the structure takes on its characteristic appearance with the scalloped edge at ground level as shown in the figure.

An entrance 15 is provided with two doors; the outer one is shown at 16. The inner door, not shown, serves to keep the structure air-tight when the outer door 16 is open. Apertures 17 are provided to equalize the pressure when it is desired to open the doors. A centrifugal pump 18 provides the air necessary to maintain inflation of the structure and to supply ventilation within the structure.

As materials for the structure, any film or fabric, coated or uncoated, capable of supporting itself upon inflation, having slight permeability and being capable of weathering the elements may be used. "Mylar"¹ polyester film, uncoated or coated, is a preferred film for the structure. Nylon fabric coated with a vinyl resin or impregnated with neoprene, Buna rubber or "Hypalon"² are among

¹ Manufactured by E. I. du Pont de Nemours & Co.

² A synthetic rubber manufactured by E. I. du Pont de Nemours.

the useful fabrics that may be used. As load-carrying members (the cables), steel bands, steel cables, "Mylar" polyester film strips or rope, nylon rope, hemp rope, etc. may be used.

The air supported structure of the present invention has been described as being a spheroidal section. One obvious deviation is the scalloped lower edge, as described, due to the construction of the gore sections. In designing the gore sections, two basic gore designs are possible: constant gore radius and decreasing gore radius from base to apex. Theoretically, a structure with constant gore radius has uniform strength from the bottom to the top of the gore, the tension on the film or fabric under a given load being proportional to the gore radius. Theoretically, the structure in which the gore radius decreases from the base to the apex is capable of withstanding greater pressure near the apex than at the base of the structure. Since tests indicate that the maximum aerodynamic lift occurs near the apex, this latter design (wherein the gore radius decreases from the base to the apex) is preferred.

The most desirable structure, as mentioned previously, is one in which cables from apex to base are used. Upon inflation, it has been found that the cables do not assume the shape of a circular arc, but rather assume a shape that is flatter at the apex and steeper at the base, i.e., an oblate spheroid.

In the following examples, air supported structures of this invention are compared to conventional air supported structures. The results indicate that a drastic improvement in the strength of air supported structures can be obtained by the structures of the present invention.

EXAMPLE I

An air supported structure having the parachute appearance and scalloped lower edge characteristic of this invention was erected in the manner described. It was composed of sixteen billowing sections or gores of 0.5 mil "Mylar" polyester film. Its diameter was 42 inches at the base and it was 14 inches high when inflated. The individual gores had radii between 22 inches and 6 inches, depending upon the internal pressure. The load-carrying members were $\frac{1}{16}$ " stranded steel cables fastened at the crown to a 3-inch diameter $\frac{1}{4}$ -inch steel plate. The structure was inflated to a pressure of 1.27 p.s.i. and no failure occurred.

As a control, a hemisphere of 0.5 mil "Mylar" polyester film having a diameter of 42 inches at the base and being 14 inches high when inflated, was inflated until the structure failed. Results are given in Table 1.

Table 1

Example	Maximum Inflation Pressure, p.s.i.	Calculated Stress at Failure
Control.....	0.73	16,600 p.s.i.
I.....	1.27	Did not fail.

EXAMPLE II

A scalloped air supported structure of this invention having 24 gore sections of 0.25 mil "Mylar" polyester film, 42 inches in diameter at the base and 14 inches high when inflated, was tested in a wind tunnel. The 23 load-carrying members were $\frac{1}{16}$ " stranded steel fastened at the crown to a 3-inch diameter $\frac{1}{4}$ " steel plate.

As a control, a hemisphere of 0.25 mil "Mylar" polyester film, 42 inches in diameter at the base and 14 inches high when inflated, was also tested in the wind tunnel. Results are given in Table 2.

Calculations indicate that the advantages apparent for the experimental models tested in the examples will provide the basis for construction of similar structures within the scope of the present invention having diameters of at least 100 feet and up to 300 feet or higher and capable of withstanding air velocities of at least 70 miles per hour. Such structures will find wide use as construction shelters, swimming pool enclosures, etc.

It is anticipated that if the structure is to be used over an extended period, then it may be advisable to erect a framework within but not necessarily in contact with the normally air-supported structure. In this event, any emergency, e.g., power failure, would not cause complete collapse of the structure. Such a framework might be a simple wooden or metal construction erected to conform substantially to the inside contour of the structure or as slats placed within sleeves in the structure as "ribs." Inflated and sealed tubular sleeves might also be used to function as "ribs" to prevent complete collapse.

It should be understood that although the examples describe structures wherein 16 and 24 gore sections were used, any number greater than about 4 will provide the advantages of the present invention. The important consideration is that by reducing the radius over which the inflating pressure is applied (by using gore sections), the tension in the film or fabric, being proportional to the gore radius, is similarly reduced.

It should also be understood that the invention is applicable not only to air supported structures entirely in the form of spheroidal sections, but to air supported structures composed partially of spheroidal sections. Thus, the invention is applicable to a structure in the form of a cylindrical section having spheroidal sections at each end. The spheroidal sections can be modified in accordance with the present invention.

As many widely different embodiments of air supported structures may be constructed within the spirit and scope of the invention, it is understood that the invention is not to be limited except as defined in the appended claims.

What is claimed is:

1. A structure supported solely by air pressure in the interior thereof, said structure comprising a plurality of gores of flexible material terminating in a lower edge; 55 said gores having a common apex, having a gore radius which decreases from the base to the apex and arranged to give said structure the form of a section of a sphere; the distance from the apex of said gores to the extremities of the base of each of said gores being less than the 60 distance from said apex to a point on the base halfway between the extremities of the base of each of said gores; and means for rendering the lower edge of said structure air-tight.

2. A structure as in claim 1 wherein cables extend from the apex of said structure to the base of said structure along lines which define said gores.

3. A structure as in claim 1 composed of "Mylar" polyester film.

4. A structure as in claim 1 having a diameter of at least 100 feet.

5. A structure supported solely by air pressure in the interior thereof, said structure comprising a plurality of gores of flexible, self-supporting, weather resistant, slightly permeable material terminating in a scalloped lower edge; said gores having a common apex, having a gore

radius which decreases from the base to the apex and arranged to give said structure a substantially hemispherical form; the distance from the apex of said gores to the extremities of the base of each of said gores being less than the distance from said apex to a point on the base **5** halfway between the extremities of the base of each of said gores; and means for rendering the lower edge of said structure air-tight.
